(57) **CLAIM**

The ornamental design for jump rope handle as shown and described.

DESCRIPTION

FIG. 1 is a front elevational view of the first embodiment of the jump rope handle showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a perspective view thereof;
FIG. 8 is another perspective view thereof;
FIG. 9 is a front elevational view of the second embodiment of the jump rope handle;
FIG. 10 is a rear elevational view thereof;
FIG. 11 is a left side elevational view thereof;
FIG. 12 is a right side elevational view thereof;
FIG. 13 is a top plan view thereof;
FIG. 14 is a bottom plan view thereof;
FIG. 15 is a perspective view thereof; and,
FIG. 16 is another perspective view thereof.
